UNITED STATES PATENT OFFICE.

MATTHIAS LUDLUM, OF FAIR HAVEN, VERMONT.

WATER-TIGHT DOOR FOR MARINE SAFES, LOCKERS, &c.

Specification of Letters Patent No. 23,477, dated April 5, 1859.

To all whom it may concern:

Be it known that I, MATTHIAS LUDLUM, of Fair Haven, in the county of Rutland and State of Vermont, have invented a certain 5 new and useful Improvement in Water-Tight Doors for Marine Safes, Lockers, and other Purposes, of which the following is a full, clear, and exact description, reference being had to the accompanying drawing, 10 which forms part of this specification, and in which—

Figure 1 represents an inside view of the door and door-frame; Fig. 2 a side or edge view of the door-frame and accompanying 15 parts; Fig. 3 a longitudinal section, and Figs. 4 and 5 transverse sections showing the door closed and partly open.

In the application of my improvement to marine safes or lockers, I here speak of the 20 door as being water-tight only, but by that it is intended to be implied that by a nice construction of the parts or by a selection of proper surface or packing material, it is or may be air tight as well. The utility of 25 such a door whether as applied to the safes, chests, or lockers of vessels of large tonnage, or of smaller craft including "life" and other boats, need not specially be descanted on here, as the importance of tight fitting 30 doors to such articles or parts is well understood, whether such articles or parts be fixtures, or detached, or detachable contrivances that in the case of a casualty may be used as floats.

35 Discarding all double or separate arrangements of parts which require extra effort or time to make the door tight, in addition to or independent of locking or fastening it and independent of what may be necessary 40 from time to time in adjustment of the parts, I adopt the simpler and readier plan of making the door self-tightening on closing, or being shut to and locked or fastened; and this I do substantially as follows.

45 Referring to the accompanying drawing, the door (A) or "lid" is connected by a hinge or hinges (a) at its one edge to the framework (B) of, say, a locker or safe to which the inner portion (b) represents metallic lining. The opposite edge of the door (A) and its adjoining frame-work may be 50 provided with ordinary or any suitable locking contrivances. Said door occupies, when closed, a recessed position in the frame-work (B), and preferably so that its outside surface is flush with, or below, the general out-

side surface of the framework or casing, or if made with moldings so that they only project beyond the general surface and which may be within moldings to the surrounding 60 framework. This door (A) I call the main or outer door as it is provided with an inner door, that, combined, forms a "double door" or lid. Thus, I make the main door (A) hollow on its inside, and face its inner portion 65 with a secondary door (C), between which and the main door is a semi-elliptic spring (D) arranged to cross the centers of the doors and kept in place by screws (d) which pass through slots in the ends of the spring so as 70 to admit of free play to the spring in its action against the inner door to press it outward, or in the action of the inner door, when forced inward, against it.

The inner door (C) is secured and kept 75 in place by means of, say, four pins, two (d', d'), on each side, passing into the edges of the inner door and having free play in corresponding slots (e, e) cut in the inside rim which forms part of or is secured to the 80 outer door, within which the inner door, thus hung and acted on by the spring (D), is made capable of play inwardly and outwardly in an easy and yielding manner partaking somewhat of the character of a "uni- 85 versal" movement.

The outer face of the inner door is covered or edged with india rubber or some other soft or elastic substance (f). While the outer door (A) has or may have its bearing proper, on being shut to, against the frame-work it is hinged to; the inner door (C) bears by its soft facing (f) against a collar (g) of an independent frame or interior "setting" (E) in such manner that 90 on shutting to the door the collar (g), which in shape is a continuous border, becomes bedded in the soft facing (f) of the inner door. Thus, the slamming-to of the outer door will not cause injury to the inner door, 95 as though the latter has the general motion of the former, it has in addition an independent motion or freedom to move and this in so yielding a manner to any required and differing extent at opposite sides, edges, or corners, as to secure in air and water (or either) tight joint being established by the embedding of the projecting collar (g) in the soft facing (f), independently of or in 100 addition to the joint formed by the junction 105 of the outer door with or against its surrounding framework.

The independent frame or interior "setting" (E), which forms by its collar (g) an independent bearing to or for the inner door, may be made of any suitable metal, 5 with an outer flange (h), cast on it, designed to bear on a soft or elastic packing (i), interposed between said flange and an inner flange (k) to the frame work (B), so as to form a tight but soft and yielding seat. 10 Said independent frame (E) is drawn to its place, and made tight or adjusted, by double wedges (l), arranged between an inner flange (m) to the frame, and a border frame (n), that may also serve to hold or bear 15 down on the edges of the metallic lining (b) of the safe. By removing the wedges (l), the independent frame (E), which is entered from the outside, may be drawn out. Such independent frame or "setting", however, 20 may be differently fastened, by the employment of any suitable mechanical equivalents to the wedges, such as screws, and the frame be altered to suit such fastenings; or, supposing the door and frame-work to be of 25 square form, but it is desired to have the opening into the safe or locker of a round figure, then the hole in the independent

frame or setting should be made round, as may also the hole in the outer frame, and said independent frame be held at the back 30 by a circular rim screwing on to it while it may be constructed to present in front a valve seat, the equivalent of the collar in the former case, for a conical valve projection from the inner door (C) to fit against 35 or in. Such or other like changes however it is hardly necessary here to note, as change of form necessarily involves more or less change in construction, and these and other changes may be made without departure 40 from the novel feature of my improvement.

What is here claimed is:

The double door (A, C), constructed and operating substantially as described, in combination with the outer or surrounding frame-work (B) and independent interior frame (E) or its equivalent, essentially as and for the purposes set forth.

In testimony whereof, I have hereunto subscribed my name.

M. LUDLUM.
